SWITCHING DEVICE

Harrison J. L. Frank, Detroit, Mich., assignor to
 Bulldog Electric Products Company, Detroit,
 Mich., a corporation of West Virginia

Application October 29, 1934, Serial No. 750,492

5 Claims. (Cl. 200—133)

This application relates to switching devices and discloses two similar switching devices, each comprising in general a sheet metal box containing a cup-shaped receptacle exposed through a hole in a front of the box for insertion thereinto and withdrawal therefrom of a fused switch plug or head cooperating with said receptacle.

Objects and features of the inventions of this application will best be understood upon reference to the appended drawings which disclose embodiments of the inventions. In these drawings,

Fig. 1 is a cutaway front view of a switching device as mounted against a vertical wall;

Fig. 2 is a section thereof;

Fig. 3 is a partial section at right angles to the view of Fig. 2, with the plug shown in the circuit-break position;

Figs. 4 and 5 show the plug and receptacle parts per se, in two different relative positions;

Fig. 6 is a partial section like Fig. 3 but showing a differently formed device.

Referring to Figs. 1-5 of the drawings, it will be seen that there is there shown a switching device including a sheet metal box 10 having a flat front 11 mounted on hinges 11a, and having knockouts (not shown) for providing cable entrance into the interior thereof, the box being shown as provided with three pairs of line and load conductors 12.

Disposed within the box and shielded therefrom by insulation sheet 14 on the back thereof and secured thereto by screws 14a is a receptacle 15. The latter is of insulation material, and is generally cup-shaped, being provided with ledges 16, on which are disposed four stationary contacts 17, these being secured in place by screws 18 which have binding nuts 19 thereon for physically and electrically connecting two pairs of the conductors 12 to the contacts 17. Since the third pair of conductors is to form a neutral line, the conductors of this pair are mutually connected by means of a neutral strap 20 disposed on the back of the receptacle and secured thereto and connecting the binding screws 21, these having binding nuts 22 thereon for connecting the conductors of the third pair to the strap, the latter being in electrical contact with the back of the box 10, substantially as shown in Fig. 3.

For cooperating with the receptacle there is provided a fused plug. The latter comprises a plug body 24 of insulation provided with a handle 25 which projects through an opening 26 in the front 11 so as to be accessible from outside the device when the front closes the box. In a wall

of the plug are two relatively isolated and barriered depressions or sockets 27 containing threaded socket shells 28 for the reception of plug fuses 29 of conventional character. A tip contact 30 in each socket shell is connected by a center screw 31 to a contact prong 32 on the wall of the plug opposite the socketed wall aforementioned. Each shell is electrically connected by a rivet 33 to a contact prong 34 disposed against the socketed wall of the plug and projecting downwardly therefrom through a slot 35 thereof. The contact prongs 32—34 are aligned with one another in pairs and connect the mutually aligned contacts 17 of the receptacle thru the socket shells and fuses. The pairs of prongs are relatively barriered by barrier grooves and ribs 36 on walls of the plug.

Secured to an end wall of the box 10 is a spring lug 38 which projects upwardly through a hole in the front cover 11 to act as a latch therefor, the spring lug for this purpose being provided with a deformation 39. The spring lug for locking the box when the front is closed has an aperture 41 for the reception of a padlock or other locking device.

The sockets 27 of the plug are formed with test slots 43 for the reception of test leads which may be inserted into the sockets for engagement with the socket shells therein, through the hole 26 of the front, even when the latter is closed and when the plug is in the receptacle.

Operation and uses of the switching device will now be described. In normal use, the parts occupy the position shown in Fig. 2, and the circuits between the conductors of the pairs are closed through the prongs 32 and 34, the tip contacts and shells of the socket shells, and the plug fuses.

When it is desired to break the circuit, for normal switching or for fuse renewal, even when the front 11 is closed, this may be done very conveniently merely by pulling the plug out of the receptacle to the plug-out position of Fig. 3. Lugs 48 formed on the plug engage the under surface of the front 11 to prevent complete withdrawal of the plug from the device, partial withdrawal being sufficient for circuit breaking, or fuse renewal. The operation of circuit breaking exposes the sockets of the plug and the fuses therein, and permits fuse renewal, the operation of fuse renewal being interlocked to the operation of plug withdrawal so that the circuits are broken before fuse renewal can be effected.

It will be observed that the plug is held in circuit breaking position by the frictioned engage-

ment between it and the receptacle; other means, such as spring lugs may be relied upon to maintain the plug partially withdrawn, if desired.

When it is desired to lock the switch in circuit breaking position, so as to prevent the circuit being made, as for example when the line is to be left open for a long time, the front 11 is opened and the plug reversed 180 degrees in the receptacle so that the prongs thereof are no longer in alignment with the contacts 17, but are received within "dead" recesses 50 in the back of the receptacle. The cover is then closed again and locked. Pulling the plug out, under such circumstances, will not do more than expose the fuses for fuse renewal. Under no conditions can the circuit be made, unless the cover 11 be unlocked and the plug reversed another 180 degrees and returned to its original position with respect to the receptacle.

20 In Fig. 6, there is shown an embodiment similar to that of Figs. 1-5 but differing therefrom in that the hingedly mounted front 11 is replaced by a front 51 mounted on lugs 52 by means of screws 53, the hinges 11a mounting a closed cover 54 having a raised portion 55, and having an opening thru which passes the spring lug 38 receiving the padlock. The raised portion 55 clears the handle 25 of the plug, when the latter is plugged into the receptacle, but the cover 54 debars access to the plug and prevents switching or fuse renewal. Not until the padlock is removed and the cover 54 swung open can the operations of switching or fuse renewal be effected; but when the padlock is removed, these operations can readily be effected, the device, with cover 54 open, being like the device of Figs. 1-5. If desired, either or both of the parts 51-54 may be locked or left unlocked.

If desired, the openings 26-56 in the fronts 11-51 may be provided with notches to clear the lugs 48 of the plugs or otherwise so dimensioned or fashioned that the plugs may be removed freely thru the front openings, in which case the fronts function only as masking plates to conceal the wiring in the gutters of the box 10 around the receptacles.

The advantages of the constructions here shown are generally to be found in the simplicity and economy of manufacture of the devices. Despite the fact that the devices can be manipulated to perform all of the functions desired in switching devices of the character under consideration, efficiently and satisfactorily from all points of view, the devices are extremely simple and economical of manufacture, as may be readily observed from an inspection of the disclosure.

It will also be observed that from all points of view, the devices are satisfactory as switching devices, and their attributes as switching devices need not be discussed in detail because they will be readily apparent to those skilled in the art.

I claim:

1. In an accessible fuse safety type switching device, an accessible contact receptacle, and a fuse carrying plug formed to be insertable into or withdrawable partially or completely from said receptacle, the plug and receptacle being complementarily formed to cooperate with each other in four different positions: when the plug is fully inserted into said receptacle, receptacle contacts are inaccessible and contact is made; when the plug is partially withdrawn the fuses thereof are exposed and receptacle contacts are inaccessible and contact is broken; when the plug is completely withdrawn from the receptacle, the fuses

thereof are exposed, the receptacle contacts are accessible, and contact is broken; and when the plug is in the receptacle in a position 180 degrees reversed from the first mentioned position the plug is held in the receptacle with the receptacle contacts in accessible but with contact broken, reversal of the plug from one fully inserted position to the other being necessarily preceded by complete withdrawal of the plug from the device, the device including personally controllable means operable optionally for preventing the plug from being completely withdrawn while permitting the plug to be partially withdrawn or for permitting the plug to be completely withdrawn.

2. A switching device of the character that comprises a casing having a main cover provided with an opening and containing a switch including a base within the casing behind the opening, a fuse carrier reciprocable through the opening towards and away from the base for switching action and carrying fuses in such a way that they may be exposed without requiring the carrier to be disassociated with respect to the base, and having a handle outside the casing whereby the carrier may be pushed towards or pulled away from the base, the carrier being so formed that when it is associated with the base it debars access to live parts of the device and being formed to be removable from the base and being capable of association therewith in circuit closing or circuit opening position, fuse exposure being possible only when the circuit is opened by pulling the carrier away from the base, the device including personally controllable means operable optionally for preventing the carrier completely from being removed from the device and exposing live contacts of the device, while permitting it to be pulled away from the base for switching and fuse exposure or for permitting the carrier to be disassociated from the base.

3. A switching device of the character that comprises a casing having a main cover provided with an opening and containing a switch including a base within the casing behind the opening, a fuse carrier reciprocable through the opening towards and away from the base for switching action and carrying fuses in such a way that they may be exposed without requiring the carrier to be disassociated with respect to the base, and having a handle outside the casing whereby the carrier may be pushed towards or pulled away from the base, the carrier being so formed that when it is associated with the base it debars access to live parts of the device and being formed to be removable from the base and being capable of association therewith in circuit closing or circuit opening position, fuse exposure being possible only when the circuit is opened by pulling the carrier away from the base, the device including personally controllable means operable optionally for preventing the carrier completely from being removed from the device and exposing live contacts of the device, while permitting it to be pulled away from the base for switching and fuse exposure or for permitting the carrier to be disassociated from the base, and means for sealing the switch in open-circuit condition with the carrier in association with the base.

4. A switching device of the character that comprises a casing having a main cover provided with an opening and containing a switch including a base within the casing behind the opening, a fuse carrier reciprocable through the opening towards and away from the base for switching

- action and carrying fuses in such a way that they may be exposed without requiring the carrier to be disassociated with respect to the base, and having a handle outside the casing whereby the carrier 5 may be pushed towards or pulled away from the base, the carrier being so formed that when it is associated with the base it debars access to live parts of the device and being formed to be removable from the base and being capable of association therewith in circuit closing or circuit opening position, fuse exposure being possible only when the circuit is opened by pulling the carrier away from the base, the device including personally controllable means operable optionally 10 15 for preventing the carrier completely from being removed from the device and exposing live contacts of the device, while permitting it to be pulled away from the base for switching and fuse exposure or for permitting the carrier to be disassociated from the base, access to live parts being attained only when the cover is open or the carrier is not associated with the base, the cover being openable even when the carrier is in circuit closing association with the base. 20 25 5. A switching device of the character that comprises a casing having a main cover provided with an opening and containing a switch including a base within the casing behind the opening, a fuse carrier reciprocable through the opening towards and away from the base for switching action and carrying fuses in such a way that they may be exposed without requiring the carrier to be disassociated with respect to the base, and having a handle outside the casing whereby the carrier may be pushed towards or pulled away 5 from the base, the carrier being so formed that when it is associated with the base it debars access to live parts of the device and being formed to be removable from the base and being capable of 10 association therewith in circuit closing or circuit opening position, fuse exposure being possible only when the circuit is opened by pulling the carrier away from the base, the device including personally controllable means operable optionally 15 for preventing the carrier completely from being removed from the device and exposing live contacts of the device, while permitting it to be pulled away from the base for switching and fuse exposure or for permitting the carrier to be disassociated from the base, access to live parts being attained only when the cover is open or the carrier is not associated with the base, the cover being openable even when the carrier is in circuit closing association with the base, and means for 20 sealing the switch in open circuit condition with the carrier in association with the base.
